UNITED STATES PATENT OFFICE.

JOHN M. SNEAD AND CASSIUS BRADY, OF CHICAGO, ILLINOIS, ASSIGNEES TO GRAVITY
COAL BIN COMPANY, A CORPORATION OF MAINE.

DUMPING-TRESTLE.

1,013,229.

Specification of Letters Patent.

Patented Jan. 2, 1912.

Application filed November 27, 1908, Serial No. 464,752. Renewed November 11, 1911. Serial No. 659,842.

To all whom it may concern:

Be it known that we, JOHN M. SNEAD and CASSIUS BRADY, citizens of the United States, residing at Chicago, in the county of Cook 5 and State of Illinois, have invented certain new and useful Improvements in Dumping-Trestles, of which the following is a specification.

The object of our invention is to provide 10 efficient means for stacking coal or other material transported in dump cars.

We have illustrated our invention in connection with a dump car of a well-known type having a normally flat floor provided 15 with drop doors hinged adjacent the longitudinal center of the car, but our improved apparatus may, without sacrificing its advantageous features, be adapted to cars of different construction.

20 In the drawings—Figure 1 is an elevational view of one form of our dumping trestle. Fig. 2 is a fragmentary section on the line A of Fig. 1. Fig. 3 is a plan view. Figs. 4 and 5 are plan views of the dumping trestle, showing different arrangements 25 of the tracks. Fig. 6 is a sectional view on line B B of Fig. 1. Fig. 7 is a sectional plan view of part of the structure shown in Figs. 1, 2, 3 and 7. Figs. 8 and 9 are a side 30 and end elevation of a retaining block or chock for holding the cars in place upon the trestle.

The yard in which the coal or other material is to be stored is provided with a 35 series of stationary railway tracks, and a portable trestle mounted upon wheels is used for the purpose of distributing the coal or other material. This trestle is provided with an inclined approach and a level ele- 40 vated platform upon which railway tracks are laid, the tracks at the base of the approach being properly beveled to fit over the stationary tracks for the purpose of permitting cars to run from the stationary 45 tracks up the inclined approach to the platform. The platform and approach are supported upon any suitable sub-structure, the latter being provided with car wheels of the ordinary form, in order that the entire 50 structure may move along the stationary tracks. The elevated platform projects beyond the supporting sub-structure the projecting end being suitably braced therefrom. An inclined deflector slopes downwardly 55 and outwardly from a point beneath the

platform, in such manner that the part of the weight of the dumped material which acts normally to said inclined deflector will force the trestle backward along the stationary track. By this means the weight of 60 the dumped materials acts automatically to move the trestle away from the dumped material, thus securing a proper distribution thereof. The stationary tracks 1 are laid throughout the area where the material is 65 to be dumped, preferably in parallel lines properly spaced to distribute the material evenly. The tracks may be surrounded by walls of any preferred height for the purpose of retaining the dumped material. In 70 the present instance we have illustrated a low wall or curbing 25 running alongside of the tracks. These curb walls may be disposed as shown in Fig. 3, the tracks 1, 1^a being arranged in pairs inclosed between 75 such curbing with a single track 1^a extending between the inclosures formed thereby.

The dumping trestle consists of a sub-structure mounted upon ordinary railway car wheels, and may if desired be built in 80 sections 2, 3 and 4, each of the length of an ordinary railway car, and each of these sections may be provided with an ordinary swiveled truck, in order to facilitate the transportation of the trestle from place to 85 place. When constructed in sections, any suitable means, such as bolts or rods, may be utilized for connecting the sections together when assembled for use. In Fig. 1 we have shown the sections secured together 90 by ordinary bolts 26. When the trestle is of double width, it is also preferably constructed in single track sections for convenience in transporting the same from place to place. Such construction is clearly illustrated in 95 Fig. 6, where the right and left halves of the trestle are held together by timbers 27 and braces 28, suitable straps 29 and angles 30 being employed for the purpose of reinforcing the structure. Preferably, the ele- 100 vated platform 5 is about fifteen feet above the level of the stationary tracks 1, this being the maximum height to which it is generally desired to pile coal on account of the pressure resulting from piles of greater 105 height. However, the height of the trestle may be differently adjusted for different materials and different conditions. In the present instance we have shown the platform 5 projecting about half a car length 110

beyond the base of the sub-structure, the projecting end being supported by diagonal timbers 6. A bumper 7 is provided near the outer end of the platform 5, and from a point about a car length inwardly from the bumper, a deflector 8 extending transversely of the structure slopes downwardly toward the end thereof. The projecting supporting timbers 6 are incased between side walls 9 and an end wall 10 as shown more clearly in Fig. 2. The side walls diverge from the timbers 6 to the deflector 8, such divergence being provided for the purpose of facilitating the movement of the trestle away from the pile of dumped material, as in the absence of such divergence there is a tendency on the part of the dumped material to tightly hold the structure against movement.

In order to dispense with the use of a locomotive for pushing cars upon the trestle, and in order to render it possible to draw one car up at a time and to lower the same after being dumped, we mount upon the substructure of the trestle a motor 11, which may be an electric motor or any other source of power. Geared to the motor is a winding drum 12, or two such drums in case the trestle is provided with two tracks, and a cable 13 extends from the winding drum over the sheaves 14 and 15 to the upper side of the trestle. Cable 13 is provided at its end with a hook or other means of attaching the same to a car. Sheaves 16 may be placed upon the upper side of the trestle to carry the cable and prevent it from contacting with the ties or rails. When the trestle is of double width, we preferably employ a single motor, as shown in Fig. 7, in which the motor is shown as operating through a train of gearing 31, 32, 33, 34, 35 and 36. Suitable clutch mechanism is provided whereby the gear 36 may be connected to the adjacent drum 12 or to the shaft 40 which is keyed to the opposite drum. Means are also provided for driving the pulley 41 from the gear 36 and any suitable brake mechanism may be employed in connection with the winding drums and the pulley 41 by which the trestle is moved from place to place.

Inasmuch as the specific construction of the brake and clutch mechanism employed forms no part of our invention and may be of any approved type, detailed description thereof will be unnecessary. The motor 11 may also be geared to one of the track wheel axles by means of a chain belt 17, or other suitable gearing, for the purpose of moving the trestle from place to place.

In Figs. 1, 2 and 3 we show a trestle of double width extending over two stationary parallel tracks 1, 1^a, the trestle also being provided with parallel tracks 1^b, 1^c registering therewith. In this form of the device, cross-over switch tracks connect the parallel

tracks upon the inclined part of the trestle, and the motor is provided with two winding drums and two cables for the purpose of handling cars upon each of the tracks. In practice, when this form of trestle is used a line of filled cars will be shunted upon one of the stationary tracks, for instance, track 1^a. The cable 13^a will then be attached to the end car, and by means of the winding drum and motor this car will be pulled up track 1^a to the elevated platform and there dumped by opening the drop doors 20 shown in Fig. 7. The switch in track 1^a being properly adjusted, the car will then be lowered upon the track 1, this track having been reserved for empty cars.

The single track trestle shown in Fig. 4 is adapted for use in those instances where it is not necessary to speedily handle a large number of cars.

The form shown in Fig. 5 may be operated in a manner similar to the double trestle shown in Fig. 3, and will answer the same purpose except for the fact that a narrower pile will be discharged therefrom owing to the use of but a single track upon the elevated platform.

We claim:

1. In a device of the class described, an elevated movably mounted platform, and a deflector extending transversely of said platform and sloping downwardly and outwardly therefrom. 95
2. In a device of the class described, an elevated movably mounted platform having an inclined approach, and a deflector extending transversely of said platform, said deflector sloping downwardly and outwardly therefrom. 100
3. In a device of the class described, an elevated movably mounted platform having an inclined approach, said platform and approach being divided into separable sections, and a deflector extending transversely of said platform and sloping downwardly and outwardly therefrom. 105
4. In a device of the class described, a stationary track, an elevated platform and inclined approach thereon, said platform and approach being mounted on wheels, and a deflector extending transversely of said platform and sloping downwardly and outwardly therefrom. 115
5. In a device of the class described, a stationary track, a dumping trestle mounted on wheels and comprising an elevated platform and inclined approach, a track on said platform and approach, and an inclined deflector sloping downwardly and outwardly from a point beneath said platform. 120
6. In a device of the class described, a stationary track, a dumping trestle mounted on wheels and comprising an elevated platform and inclined approach, a track on said platform and approach, an inclined deflec- 125
- 65

- tor sloping downwardly and outwardly from a point beneath said platform, and means mounted on said trestle for propelling cars.
7. In a device of the class described, a stationary track, a dumping trestle mounted on wheels and comprising an elevated platform and inclined approach, a track on said platform and approach, an inclined deflector sloping downwardly and outwardly from a point beneath said platform, and means mounted on said trestle for propelling cars and moving said trestle on said stationary track.
8. In a device of the class described, a stationary track, a dumping trestle mounted on wheels and comprising an elevated platform and inclined approach, a track on said platform and approach, an inclined deflector sloping downwardly and outwardly from a point beneath said platform, a motor and drum mounted on said trestle, a cable co-acting with said drum to propel cars, and gearing between said motor and the track wheels of said trestle.
9. In a device of the class described, a stationary track, a dumping trestle mounted on wheels, said dumping trestle comprising a supporting sub-structure, an inclined approach and an elevated platform projecting beyond said sub-structure, supports extending outwardly from said sub-structure to the under side of said platform, and a casing inclosing said supports, the sides of said casing diverging toward said sub-structure.
10. In a device of the class described, parallel stationary tracks, a dumping trestle mounted on wheels, said trestle comprising a supporting sub-structure, an elevated platform and an inclined support, parallel tracks on said approach and platform and cross-
- over tracks and switches between said last named parallel tracks.
11. In a device of the class described, parallel stationary tracks, a dumping trestle mounted on wheels, said trestle comprising a supporting sub-structure, an elevated platform and an inclined approach, parallel tracks on said approach and platform and cross-over tracks and switches between said last named parallel tracks, and motor winding drums and cables mounted on said trestle.
12. In a device of the class described, a dumping trestle comprising two series of separable sections, each section being mounted on wheels, and means whereby the members of each series may be connected together in alinement on a single track and whereby the two series lying in parallel tracks may be connected together.
13. In a device of the class described, a dumping trestle comprising two series of separable sections, each section being mounted on wheels, means whereby the members of each series may be connected together in alinement in a single track and whereby the two series lying in parallel tracks may be connected together, a motor and winding drum on one of the trestle sections, a drum on the opposite section, a shaft extending from the motor to said last named drum, and clutch mechanism whereby movement may be imparted to either drum.

In testimony whereof, we have subscribed our names.

JOHN M. SNEAD.
CASSIUS BRADY.
